PATIO TABLE

David Le Roy Creswell, Pasadena, Calif.

Application March 27, 1951, Serial No. 14,641

Term of patent 7 years

(Cl. D33—14)

To all whom it may concern:

Be it known that I, David Le Roy Creswell, a citizen of the United States, residing at Pasadena, in the county of Los Angeles and State of California, have invented a new, original, and ornamental Design for a Patio Table, of which the following is a specification, reference being had to the accompanying drawing, forming part thereof.

Figure 1 is a view in top plan of a patio table embodying the new design, the upper portion of the figure being broken away to allow for the required top margin, said broken away portion being similar to the lower portion of the figure;

Figure 2 is a view in side elevation the brick work pattern base being circular, the opposite side appearing similar to what is shown.

I claim:

The ornamental design for a patio table, substantially as shown and described.

DAVID LE ROY CRESWELL.
